UNITED STATES PATENT OFFICE.

GEORGE TUPPER BROWN, OF BALTIMORE, MARYLAND, ASSIGNOR OF ONE-HALF TO THE McCORMICK & COMPANY, OF SAME PLACE.

DESIGN FOR A PERFUMERY-BOTTLE.

SPECIFICATION forming part of Design No. 27,259, dated June 29, 1897.

Application filed April 24, 1897. Serial No. 633,806. Term of patent 7 years.

To all whom it may concern:

Be it known that I, GEORGE TUPPER BROWN, a citizen of the United States, residing at Baltimore, in the State of Maryland, have 5 invented and produced a new and original Design for a Perfumery-Bottle, of which the following is a specification, reference being had to the accompanying drawing, forming part of this specification, in which—

c The drawing represents my design for perfumery-bottles.

As shown in the drawing, the leading or characteristic features of my design consist of a flat triple-step truncated cone A, a globu-

lar body B, having a series of annular graduated ridges b, formed on its periphery and integral with a collar b', the stopple C, with a chimney c, and a corrugated shade c'.

The design as a whole has the general appearance of a lamp of novel form and contour. 20

What I claim is—

The design for a bottle substantially as herein shown and described.

GEORGE TUPPER BROWN.
